UNITED STATES PATENT OFFICE

2,452,893

ELECTRON LENS ASSEMBLY

Charles H. Bachman, Scotia, N. Y., assignor to
General Electric Company, a corporation of
New York

Application May 31, 1946, Serial No. 673,218

4 Claims. (Cl. 250—162)

1

My invention relates to electron lens systems of the electrostatic type and it has for its primary object to provide a new and improved electron lens structure which is both easy to assemble and assures accurate alignment.

In electrostatic lenses, such as are used in electron microscopes and similar applications, high potentials are usually applied across relatively short gaps and leakage paths. It is desirable that the lens be of such geometry that it gives both greatest possible electrical safety and yet is easy to assemble and assures accurate alignment. Furthermore, in order that the aberrations of the lens be a minimum, it is essential that the apertures of the various electrode elements be centered on the optical axis and that the electrodes themselves be accurately parallel. Accordingly, it is another object of my invention to provide a new and improved electron lens system in which centering of the apertures of the various electrodes is obtained with accuracy and facility.

It is still another object of my invention to provide a new and improved electron lens assembly in which the leakage path through the supporting insulators for the various electrodes is considerably greater than the physical spacing of the electrodes.

It is a further object of my invention to provide a new and improved electron lens assembly which employs insulators which require accuracy in one dimension only.

One of the features of my invention is the use of a plurality of cylindrical insulators to support and space the electrodes of an electron lens assembly. The individual insulators need be accurate in one dimension only. Yet the assembly provides both axial alignment of the electrodes and centering of all the electrodes along the optical axis of the assembly.

The objects and advantages of my invention may best be understood by reference to the following description taken in connection with the accompanying drawing and the features of novelty which I desire to protect are pointed out with particularity in the appended claims. In the drawing Fig. 1 is a vertical sectional view of an insulator suitably embodying the invention; Fig. 2 is a cross-section of the assembly of Fig. 1 taken along the line 2—2; Fig. 3 is a vertical sectional view of a modification of the assembly of Fig. 1; and Fig. 4 is a cross-sectional view of the assembly of Fig. 3 taken along the line 4—4.

Referring to Figs. 1 and 2 jointly, I have there shown an electron lens assembly which comprises

2

a metallic outer cylinder 1 which is provided with an accurately machined inner bore and a plurality of disk-like electrodes 2—4 which are fitted within the cylinder 1. The outer electrodes 2, 4 may project inwardly toward the center electrode 3 a distance sufficient to provide desired spacing between the electrodes so that a desired lens effect is obtained. The electrodes 2—4 are provided with respective center apertures 5—7, the central aperture 6 in the intermediate electrode being larger than the apertures 5, 7. The electrodes 2—4 may be formed of any suitable conducting material, for example chrome-plated brass, and for the purposes to be pointed out later have accurately machined outer surfaces. In this fashion, the electrodes 2, 4 fit smoothly on the inner surface of the cylinder 1.

In order that the electrodes 2—4 may be accurately aligned axially and centered with respect to the optical axis of the assembly, I provide three cylindrical insulators 8—10. While the insulators 8—10 may be formed of any suitable material, such as porcelain, steatite, or Mycalex, I have found glass of the type known as Pyrex to be especially suitable in an electron lens assembly. The insulator 8 is ground or prepared on its outer surface to fit smoothly within the cylinder 1 and is provided with a centrally located raised portion 11 which is carefully prepared with an inner surface 12 which is concentric with the outer surface of the insulator 8. The electrode 3 is arranged to fit on the surface 12 so that the aperture 6 is held in accurate axial alignment within the cylinder 1. The insulating spacers 9, 10 are carefully prepared with their ends parallel and with accurately measured lengths. Preferably, the length of the insulators 9, 10 plus the thickness of the electrode 3 is greater than the length of the insulator 8. Such dimensioning and proportion of thickness of insulator 8 and of the length of insulators 9, 10 provides for ease in assembly of the lens and accuracy in alignment both axially and with respect to the optical axis of the lens. The dimensions of the diameters of the cylindrical insulators 9 and 10 are not critical. Thus, these insulators are free to move in a direction transverse to the axis of the cylinder 1.

The various elements of the assembly are held in fixed relation with respect to each other and against movement by means of a clamping system which may include a ring 13 adapted to fit within the bore of cylinder 1 below the electrode 4 and which engages a stop, shown as the head of a screw 14 threaded into the wall of cylinder 1. At the opposite end of the assembly the cylin-

drical sleeve 15 provides means for holding the various elements of the assembly in fixed position. Thus, when pressure in a downward direction is exerted on the sleeve 15, this sleeve engages the outer edge of the electrode 2. Pressure is transmitted through the insulators 9, 10 and the electrodes 3, 4 against the retaining ring 13. In an electrostatic lens of this type, the electrodes 2, 4 are maintained at the potential of cylinder 1, being in conductive contact with that cylinder. Operating potential for the electrode 3 is supplied thereto by a longitudinally extending conductor 16 which is connected to the electrode 3 and passes through an aperture (not shown) in the outer electrode 4.

In the assembly of Fig. 1, the insulators 9, 10, and 11 provide a relatively long leakage path between the outer electrodes and the center electrodes 3. The outer electrodes have centrally positioned symmetrically cup-shaped portions which are directed inwardly toward the center electrode to effect a configuration of the electric field in the vicinity of the apertures 5-7 to obtain the lens action desired. Furthermore, the insulator 8 at the point of greatest potential gradient, its point of contact with the center electrode 3, is made thicker than at any other point to inhibit electrical breakdown by rupture of the insulating material. The accurately machined outer edges of the electrodes 2, 4 together with the accurately machined bore of cylinder 1 assures centering of the apertures of these electrodes with respect to the optical axis of the system. Similarly, centering of the electrode 3 on the optical axis is provided by the accurately centered surface 12 on the insulator 8. As a result, aberration of the composite lens structure is held to a minimum. Axial alignment of the respective electrodes is maintained by the accurately dimensioned lengths of the insulators 9, 10.

In the compound cylinder type electrostatic lens assembly of Figs. 3 and 4, I have shown a structure which is suitable for applications in which it is not convenient to use the symmetrically cup-shaped electrodes 2, 4, shown in Fig. 1. Thus, in an electron microscope for example, it is desirable to place an object which is being examined as close to the lens as possible and still be able to move that object freely in space relative to the lens for focusing, as well as examining selected areas of the object. To provide this desired freedom, the structure of the assembly of Figs. 3, 4 is made asymmetrical, the outer electrode 17 being made planar and the intermediate electrode 18 and outer electrode 19 being provided with asymmetrical centrally positioned cup-shaped portions. These electrodes are assembled within the cylinder 1 and employ the same insulators 8-10 which are used in the assembly of Fig. 1 to provide both axial alignment of the respective electrodes and centering of the intermediate electrode 18. In this assembly I have shown the retaining ring 13 and screw 14 as positioned at the end closer to the apertures of the electrodes in order that an object to be examined may be positioned as close to the aperture 5 as is possible. The sleeve 15 is therefore positioned at the opposite end of the assembly.

An important advantage of my improved lens assembly is that the dimensions of the insulators employed for supporting and aligning the electrodes need be accurate in one direction only. Thus the insulator 8 requires accurate dimensioning only of its outer diameter and of the sur-

face 12 while the insulators 9, 10 are accurately dimensioned in length only. By employing a pair of offset lenses, in conjunction with a combination of such insulating cylinders, and by controlling the amount of offset, a long electrical leakage path between electrodes is provided. At the same time, the assembly of insulators provides accurate centering with respect to the optical axis and accurate spacing axially of the respective electrodes. In this fashion, not only are the electrical characteristics of the system, so far as breakdown is concerned, improved, but at the same time the optical properties of the lens are enhanced.

15 While the invention has been described by particular embodiments, it will be understood that numerous modifications may be made by those skilled in the art without departing from the invention and I therefore aim in the appended 20 claims to cover all such equivalent variations as fall within the true spirit and scope of my invention.

What I claim as new and desire to secure by Letters Patent of the United States, is:

25 1. An electrostatic electron lens structure comprising a supporting cylinder, three circular electrodes arranged coaxially within said cylinder and provided with central apertures, the outer of said electrodes being supported directly by said cylinder and having their apertures aligned thereby, first insulating means of accurately dimensioned thickness for supporting the intermediate of said electrodes within said cylinder and for aligning the apertures thereof with the apertures of said outer electrodes, and additional insulating means of accurately dimensioned length positioned between said outer electrodes and said intermediate electrode for spacing said outer electrodes axially within said cylinder.

30 2. An electrostatic electron lens structure comprising a supporting cylinder, three circular electrodes arranged coaxially within said cylinder, the outer of said electrodes being supported directly by said cylinder and having their apertures aligned thereby, two of said electrodes having centrally located offset portions extending toward the third of said electrodes, first insulating means of accurately dimensioned thickness for supporting the intermediate of said electrodes within said cylinder and for aligning the apertures thereof with the apertures of said outer electrodes, and additional insulating means of accurately dimensioned length positioned between said outer electrodes and said intermediate electrode for spacing said electrodes axially within said cylinder.

35 3. An electrostatic electron lens structure comprising a supporting cylinder, three circularly symmetrical electrodes arranged coaxially within said cylinder, the outer of said electrodes being supported directly by said cylinder and having their apertures aligned thereby, means including an insulator of accurately dimensioned thickness for centering the intermediate of said electrodes on the optical axis of said structure and for aligning the apertures thereof with the apertures of said outer electrodes, and means including a pair of insulators of accurately dimensioned length positioned between said outer electrodes and said intermediate electrode for aligning said electrodes axially of said cylinder.

40 4. An electron lens comprising a supporting cylinder, three circularly symmetrical electrodes spaced coaxially within said cylinder, the outer

of said electrodes being supported directly by said cylinder and having their apertures aligned thereby, two of said electrodes having centrally located offset portions extending toward the third of said electrodes, means including an insulator of accurately dimensioned thickness for centering the intermediate of said electrodes with respect to the optical axis of said lens, and means including a pair of insulators of accurately dimensioned length positioned between said outer **10** electrodes and said intermediate electrode for aligning said electrodes axially of said cylinder.
